REMOTE VISUAL READOUT DEVICE

Daniel A. Seltzer, Hamilton, Ohio, assignor to Gamon-Calmet Industries, Inc., Florence, Ky.

Filed Mar. 16, 1971, Ser. No. 125,003

Term of patent 14 years

Int. Cl. D14—02

U.S. Cl. D26—5

FIG. 1

FIG. 2

FIG. 3

FIG. 4

FIG. 5

FIG. 6

FIG. 7

FIG. 1 is a front elevational view of a remote visual readout device embodying my new design;

FIG. 2 is a right side elevational view thereof;

FIG. 3 is a top plan view thereof;

FIG. 4 is a bottom plan view thereof;

FIG. 5 is a rear elevational view thereof;

FIG. 6 is a left side elevational view thereof; and

FIG. 7 is a perspective view thereof.

I claim:

The ornamental design for a remote visual readout device, as shown.
